ROTARY JET ENGINE

Isadore Margolis, Baltimore, Md.

Application June 28, 1945, Serial No. 602,006

3 Claims. (Cl. 60—35.6)

1

This invention relates to jet engines.

An object of this invention is to provide a multiple jet engine having the jets radially arranged and supported for rotation about a central bearing.

A further object of this invention is to provide an engine of this type which is of relatively simple construction and provides for building up of fluid pressure in proportion to the speed of rotation of the device.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail front elevation, partly broken away, of a combined jet engine and propeller constructed according to an embodiment of this invention.

Figure 2 is a sectional view taken on the line 2—2 of Figure 1.

Figure 3 is a fragmentary sectional view taken on the line 3—3 of Figure 2.

Figure 4 is a fragmentary sectional view taken on the line 4—4 of Figure 2.

Figure 5 is a fragmentary sectional view of one of the fuel jet members.

Figure 6 is a plan view of a modified form of this invention.

Figure 7 is a fragmentary sectional view taken on the line 7—7 of Figure 6.

Figure 8 is a fragmentary sectional view taken on the line 8—8 of Figure 6.

Figure 9 is a detail side elevation of one of the jet housings.

Figure 10 is a fragmentary sectional view, partly in detail, of the rotary fuel feeder.

Figure 11 is a fragmentary sectional view showing a portion of the impeller and a means for securing the impeller to the rotary housing.

Referring to the drawings the numeral 15 designates generally a hub housing structure which is constructed of complementary housing members, including a front plate 16 having a longitudinal flange 17, and diametrically opposite bosses 18. A pair of semi-annular housing members 19, formed with flanges 20, are secured together rearwardly of the housing member 16 and are provided with forward flanges confronting the flanges 17 and secured thereto by fastening members 21.

The housing 15 has mounted therein the outer race 22 of an anti-friction bearing, the inner race 23 being secured to a stationary hub structure generally designated as 24. The stationary hub

2

structure 24 includes an annular flange 25 formed with openings 26 by means of which the flange may be secured to a stationary support and a cylindrical bushing 27 extends forwardly from the flange 25 and abuts against the inner race 23. The inner race 23 is mounted about a cylindrical air intake housing 28 which is formed with a forward or inner flange 29 against which the inner race 23 is adapted to abut. The bushing 27 is threaded on the housing 28 and tightly binds the inner race 23 against the flange 29.

The intake housing 28 includes a rear wall 30 formed integral with the cylindrical side wall of housing 28 and an air conducting nipple 31 extends from the rear wall 30. A tubular member 32 is connected at one end to the nipple 31, and at the other end to the coupling 33 which is carried by the rear end of a tubular member 34. The tubular member 34 is threaded into a central opening 35 formed in the rear wall 30 and an axially disposed jet 36 is carried by the inner end of the tubular member 34. A fuel reservoir 37 extends downwardly from the tubular member 34, and has a suction pipe 38 extending downwardly thereinto to a point close to the bottom wall 39 thereof and the pipe 38 is then extended upwardly and forwarded on an obtuse angle, as indicated at 40 and terminates within the tubular member 34. In this manner the forwardly moving air in the tubular member 34 will draw in fuel which rises in the fuel pipe 38.

A threaded plug 41 is threaded into the rear end of the pipe or tubular member 34. The housing 15 includes oppositely disposed bosses or hub members 18 which are adapted to tightly clamp the inner ends of radially arranged and oppositely extending hollow arms 42. The arms 42 are provided with enlarged inner ends 43 engaging in an annular recess 44 formed in each of the hubs or bosses 18, so that the arms 42 will be tightly clamped to the housing 15. The arms 42 are hollow and are provided on their leading sides with an elongated air intake opening or scoop 45. The air is adapted to enter the openings 45 and then move radially inwardly through the arms 42 into the interior of the housing 15. An impeller, generally designated as 46, is mounted centrally of the housing 15, and includes a plurality of impeller blades 47 secured to a hub 48, and having an outer ring 49 fixed relative thereto and firmly secured in the housing 15. The hub 48 is provided with a central bore 50 through which the forwardly moving combined air and gases are adapted to pass and the rear end of the hub 48 is of tapered construction, as indicated at 51, and rotatably engages a tapered seat 52 formed in the forward end of a bushing 53 which engages about the jet 36.

The combined air and gases which move forwardly in the bore 50, are then adapted to pass

through a nipple 54 threaded into the forward end of the impeller hub 48 and the nipple 54 has extending at right angles therefrom, nipples 55. The gas conducting tube 53 extends axially through the arms 42 and is connected to a nipple 55 by means of a coupling 57. Each arm 42 has secured to the outer end thereof, a substantially ovoidal combustion housing 58 which is closed at its leading end and has connected to the rear or trailing end thereof a substantially conical discharge member 59. The discharge member 59, as shown in Figure 3, has formed integral with the forward end thereof, a trailing end portion 60, of the housing 58, which is threaded into the housing 58, as indicated at 61. The conical discharge member 59 forms a Venturi tube with the housing 58 so that the exploded gases may be discharged and may expand as they are discharged for forcing the arms 42 to rotate and to carry therewith the housing 15.

The outer ends of the gas conducting tubes 56 are connected to a gas discharge nozzle 62 which is threaded through the housing 58. The nozzle 62, which is shown in greater detail in Figure 5, includes a housing, generally designated as 63, which is formed of a threaded cylindrical body 64 having both internal and external threads whereby the body 64 may be threaded into the housing 58. An annular flange 65 extends from the inner end of the body 64, and is adapted to abut against the outer side of the housing 58. A substantially conical nipple 66 extends inwardly from the flange or nut member 65 and is formed with a tapered valve seat 67 against which a ball valve 68 is normally held by means of a spring 69. The nipple 66 is formed with a central passage or bore 70 which is normally closed when the valve 68 is seated. A jet member 71, which is formed with a cylindrical body 72, is threaded internally of the body 64, and is provided with a jet opening 73 through which the unburned gases are adapted to be discharged into the housing 58. The spring 69 bears at its upper end against the nozzle 71 and the spring 69 may be tensioned by inward threading of the body 72. Fuel, which is discharged into the combustion chamber 74 formed in the ovoidal housing 58, is adapted to be ignited by means of an igniter 75 in the form of a spark plug. The spark plug 75 has connected thereto a conductor 76 which extends through the arm 42 and is connected to a commutator ring 77 carried by the rear end of the housing 15. The commutator ring 77 is insulated from the rear end of the housing 15, by means of an insulating ring 78. A contact member 79 is carried by the flange 25 and connected through a conductor 80 to a source of electric current supply preferably at high tension so that a spark will be generated between the opposed electrodes of the spark plug 75.

The forward side of the housing member 16 has extending therefrom a centrally disposed bolt 81 which is fixed relative to the housing member 16. The hub 82 of a propeller blade structure 83 is mounted on the bolt or shaft 81, and secured thereon by means of a nut 84 threaded on the bolt or shaft 81. A washer 85 is interposed between the nut 84 and the hub 82. Preferably the blades of the propeller 83 are disposed at right angles to the arms 42, as shown in Figure 1.

Referring now to Figures 6 to 11 inclusive there is disclosed a modified form of this invention. The engine shown in Figures 6 to 11 inclusive includes a rotary housing 15a which is similar to the housing 15, and which has mounted on the

radial boss 18a thereof, the inner ends of a pair of hollow radial arms 42a. The arms 42a are provided with annular ribs 86 engaging in annular channels 87 formed in the boss 18a so that the arms 42a will be held against endwise movement. The housing 15a is rotatably mounted on a stationary housing member 88, including a cylindrical body 89 having a forward flange 90 formed with openings 91 for bolted securing of the housing 88 to a stationary support 88a. An anti-friction bearing 92 is interposed between the rear end of the housing 15a, and an inner intake housing 93 of cylindrical configuration, which is similar to the air intake housing 28. The air intake housing 93 has mounted in the forward end thereof impeller blades 94, having a cylindrical outer rim 95. The rim 95 is secured, relative to the housing 15a, by means of set screws 96, as shown in Figure 11.

The housing 93 includes a rear wall 97 having a rearwardly tapering discharge opening 98 communicating with a pipe 99. The pipe 99 is connected to a threaded nipple 100 carried by the rear wall 97 by means of a coupling member 101. An L-shaped connector 102 is connected at one side thereof by means of a coupling 103 to the rear end of the air conducting pipe 99 and the other side of the coupling member 102 is connected to a housing 104. The housing 104 is disposed rearwardly of the housing 93 and is connected thereto by means of a threaded connector 105.

The connector 105 is formed with a central bore 106 through which the air is adapted to pass. The housing 104 includes an air chamber 107 having an adjustable needle valve 108 disposed therein, which is adjustable relative to a needle valve seat 109. The needle valve 108 is adjustable by means of a handle 110, extending from the rear wall 111 of the housing 88. The housing 93 has extending axially from the rear wall 97 thereof, a bushing 112 formed with a rear wall 113, with which the coupling member 105 is connected. The fuel conducting member 114 is connected at one end to the housing or bushing 112, and communicates with a fuel passage 115 formed in the bushing 112 and communicates with the interior thereof. The connector 114 is connected at the rear end thereof to the housing 104 and communicates with a fuel passage 116 formed in the housing 104, which passage is regulated by means of an adjustable needle valve 117.

The housing 104 is formed with a fuel chamber 118 and the fuel supply pipe 119 is in communication through a passage 120 with the fuel chamber 118. The impeller 94 includes a central hub 121 formed with a rearwardly extending tapered member 122. An elongated externally threaded fuel forcing or feeding member 123 extends from the rear end of the tapered member 122 and is loosely mounted within the bushing 112. The feeding member 123 has the rear end thereof spaced from the rear wall 113, and the rear end of the feeding member 123 is formed with a recess 124 which communicates with an axial bore 125 extending through the feeding member 123, the tapered member 122 and the hub 121. An air nozzle 126 is carried by the connector 105 and extends loosely in the bore 125 and is adapted to discharge air centrally in the bore 125 which forwardly of the nozzle 126 forms a mixing chamber.

A Y-shaped coupling 127 is connected to a nipple 128 carried by the hub 121, and oppositely

extending fuel conducting pipes 130 and 131 are connected to the branches of the coupling member 129.

As shown in Figures 6 and 7, the arms 42a have mounted on the outer ends thereof, angularly disposed jet housings 132. The housings 132 include a dome-shaped nose 133 threadably mounted in a hollow body 134 and a rearwardly flared discharge member 135 communicates with the rear end of the housing 132 and forms a venturi by means of which the exploded gases may expand. The interior of the discharge member 135 is lined by means of a lining 136 and the rear end portion of the housing 134 is also lined as at 137. The linings 136 and 137 are preferably formed of metal which will not readily burn under extreme heat.

The arms 42a are each provided with an intake opening 138 on its leading side adjacent the housings 132, and the opening 138 may have a grill 139 thereon to prevent large particles from entering the interior of the radial arms 42a. Each arm 42a also has disposed in the outer end portion thereof, a plurality of inwardly extending arcuate baffles 140 by means of which the incoming air will be directed toward the inner ends of the arms 42a as these arms rotate or swing.

In the use and operation of this device and referring particularly to Figure 2, the housing structure 15 may be initially rotated by suitable power means which will give the device an initial start. As air is drawn into the openings 45, and this air forced through the intake housing 28 by the impeller blades 47, fuel will be drawn through the fuel pipe 38 into the mixing member 34, and this fuel then discharged into the duct or bore 50. As the fuel passes outwardly through the conducting members 56 this fuel will force the ball valve 68 to unseat and discharge the fuel into the combustion chamber 74. The igniter 75 will ignite the fuel in the chamber 74 which will then discharge through the venturi 59 and the expansion of the discharged fuel or burned gases will effect rotation of the device.

The structure shown in Figures 6 to 11 inclusive will operate in the same manner as the structure shown in Figures 1 to 5, with the exception that in Figures 6 to 11 inclusive the inner ends of the propellers 83a are secured to radial bosses 141 formed on the housing 15a at right angles to the arms 42a. The fuel which is forced outwardly through the fuel conducting pipes 130 and 131 is discharged into the combustion chamber 142 formed in the housing 132 through a jet member 143. The fuel in the combustion chamber 142 is ignited by means of an igniter 144 which is connected by means of a conductor 145 to a commutator ring 146. The commutator ring 146 is engaged through a contact member or wiper 147 carried by a housing 148 which is fixed relative to the flange 90 and the conductor 149 is connected to the contact 147 and to a source of electric current supply.

What is claimed is:

1. A jet engine of the kind described comprising a supporting member, a rotatable housing member carried by said supporting member, oppositely extending hollow arms on said housing member, an ovoidal combustion chamber carried by the outer end of said arms, said arms having an air intake opening adjacent the outer ends thereof, a mixing chamber in said supporting member, impeller blades carried by said housing member

forcing air from said arms into said mixing chamber, jet means discharging fuel into said mixing chamber for mixture with the air in said chamber, means conducting the fuel charge to said combustion chamber, and means igniting the fuel charge in said combustion chamber, said fuel discharging means including a cylindrical housing in said supporting member, an elongated fuel feeding member fixed on said rotatable housing rotatable in said cylindrical housing, said fuel feeding member formed with an axial bore therethrough and an air jet fixed to said supporting member extending into said cylindrical housing for mixing the fuel and air therein.

15 2. A jet engine of the kind described comprising a supporting member, a rotatable housing member carried by said supporting member, oppositely extending hollow arms on said housing member, an ovoidal combustion chamber carried
20 by said arms, said arms having an air intake opening adjacent the outer ends thereof, a hub on said housing member having an axial bore therein, a mixing chamber in said supporting member, means conducting the fuel charge to
25 said combustion chambers, a bushing in said supporting member, said housing member having a tapered member engaging in said bushing, said tapered member formed with a bore therethrough communicating with said mixing chamber and
30 said conducting means, and means igniting said charge in said combustion chambers.

3. A jet engine comprising an annular supporting member, a forwardly opening air intake opening in said supporting member, a concentric forwardly opening tapered bushing in said housing member, said bushing providing a mixing chamber, means conducting air from said intake opening to said bushing, jet means discharging fuel into said bushing, a rotatable housing member carried by said supporting member, oppositely extending hollow arms on said housing member, said arms formed with an air intake opening adjacent the outer ends thereof, an ovoidal combustion chamber carried by said arms, a hub on said housing member, a tapered member on said hub extending into said bushing, impeller blades fixed on said hub adjacent said supporting member for forcing air into said intake opening in said supporting member, said hub formed with a concentric bore communicating with said mixing chamber, means conducting the fuel charge from said mixing chamber to said combustion chambers, and means igniting said fuel charge in said combustion chamber.
